UNITED STATES PATENT OFFICE.

ADAM DENNIS, OF FINDLAY, OHIO.

ADJUSTABLE WINDOW SHADE AND CURTAIN BRACKET.

No. 824,067.

Specification of Letters Patent.

Patented June 19, 1906.

Application filed August 11, 1905. Serial No. 273,704.

To all whom it may concern:

Be it known that I, ADAM DENNIS, a citizen of the United States, residing at Findlay, in the county of Hancock and State of Ohio, have invented a new and useful Improvement in Adjustable Window Shade and Curtain Brackets, of which the following is a specification.

My invention relates to improvements in window shade and curtain brackets; and the objects of the improvement are, first, to provide a bracket for supporting window-shades and window-curtains independent of each other; second, to provide this bracket with adjustable fixtures adapted to receive and support window-shades of various widths without removing the bracket from the window-facing.

I attain these objects by the mechanism illustrated in the accompanying drawings, in which—

Figure 1 is a perspective of the left-hand bracket; Fig. 2, a side view of same; Fig. 3, a perspective of the right-hand bracket, and Fig. 4 a side view of same.

Like numerals of reference indicate like parts of the invention.

The reference-numeral 1 designates the back of a left-hand bracket, having attached near its upper end a horizontal extending arm 2, with circular recess near its outer end adapted to support the end of a curtain-pole and a brace 3 supporting said arm. Near the lower end of said back 1 the left shade-fixture 4 is attached at right angles to an adjustable slide 5, having a forked end adapted to fit in rectangular groove 6 and be made fast by tightening the screw 7.

The reference-numeral 8 designates the back of the right-hand bracket, having attached near its upper end a horizontal extending arm 9, with a circular recess near its outer end adapted to support the end of a curtain-pole and a brace 10 supporting said arm. Near the lower end of said back 8 the right shade-fixture 11, is attached at right angles to an adjustable slide 12, having a forked end adapted to fit in rectangular groove 13 and to be made fast by tightening the screw 14.

50 In operation the brackets are fastened in

position on the window-facing by means of screws 7 and 7^a, Fig. 1, and 14 and 14^a, Fig. 3. By slightly loosening the screws 7 and 14 the adjustable slides may be moved in or out, as desired, for different widths of window-shades and made fast and held rigidly in position by again tightening said screw.

From the foregoing it will be seen that I provide a very useful and convenient device for supporting window-shades and window-curtains independent of each other, that my device obviates the necessity of mutilating the window-facing with nails and tacks and prying instruments whenever occasion requires the removal of the shade or curtain fixtures, and that by means of the adjustable slides various widths of window-shades may be used without removing the fixtures from their original position.

Having thus described my invention, I claim—

1. The combination and arrangement of the parts constituting the adjustable window shade and curtain bracket, and consisting of a back having a rectangular groove near its lower end, a horizontal extending arm near its upper end, a circular recess near the outer end and a brace supporting said arm, an adjustable slide having one forked end consisting of two rectangular tines adapted to engage with a clamping-screw in said rectangular groove, and a shade-fixture attached at right angles to the other end of said adjustable slide, substantially as described and set forth.

2. In an adjustable window shade and curtain bracket, the combination with a back having a rectangular groove, of a horizontal extending arm with brace-support and circular recess near its outer end, an adjustable slide having one forked end consisting of two rectangular tines, a clamping-screw and washer engaging therewith in said rectangular groove, a shade-fixture attached at right angles to the other end of said adjustable slide, substantially as described and set forth.

ADAM DENNIS.
